UNITED STATES PATENT OFFICE.

SILAS J. HUDSON, OF AKRON, OHIO.

DESIGN FOR A LAMP.

Application filed April 14, 1924. Serial No. 9,245. Term of patent 14 years.

To all whom it may concern:

Be it known that I, SILAS J. HUDSON, a citizen of the United States, residing at Akron, in the county of Summit and State of Ohio, have invented a new, original, and ornamental Design for Lamps, of which the following is a specification, reference being had to the accompanying drawings, forming a part thereof.

In the drawings:

I claim:

The ornamental design for a lamp, as shown.

SILAS J. HUDSON.
